GRASS CATCHER

Joe Leader, 9115 W. 34th St.,
Minneapolis, Minn. 55426

Filed Mar. 27, 1972, Ser. No. 238,753

Term of patent 14 years

Int. Cl. D15—03, 99

U.S. Cl. D40—1 A

FIG. 1 is a perspective view of a grass catcher embodying my new design;

FIG. 2 is a top view thereof;

FIG. 3 is a bottom plan view thereof;

FIG. 4 is a side elevational view thereof;

FIG. 5 is a front elevational view thereof;

FIG. 6 is a rear elevational view thereof; and

FIG. 7 is a fragmentary vertical sectional view taken along line 7—7 of FIG. 5.

I claim:

The ornamental design for a grass catcher, as shown and described.
